(57) **CLAIM**

The ornamental design for a folding handle ratchet binder, as shown.

DESCRIPTION

FIG. 1 is a top, front, and side perspective view of a folding ratchet binder, showing my new design.

FIG. 2 is an expanded view of the knob portion of the folding ratchet binder.

FIG. 3 is side view elevation of FIG. 1.

FIG. 4 is an opposite side view elevation of FIG. 1.

FIG. 5 is a front view of the folding ratchet binder.

FIG. 6 is a back view of the folding ratchet binder.

FIG. 7 is the front view of the folding ratchet binder of FIG. 5 with the handle folded.

FIG. 8 is the back view of the folding ratchet binder of FIG. 6 with the handle folded.

FIG. 9 is a bottom view of the folding ratchet binder.

FIG. 10 is an alternate bottom view of the folding ratchet binder; and,

FIG. 11 is a view of the top of the handle of the folding ratchet binder.

The broken lines shown in FIGS. 1, 2, 3, 4, 5, 6, 7, 8, 9 and 10 are for the purpose of illustrating the eye, chain and hook attached to the ratchet binder and form no part of the claimed design.
